CLAIM

The ornamental design for the switching device, as shown and described.

DESCRIPTION

FIG. 1 is a front elevational view of a switching device showing my new design;

FIG. 2 is a rear elevational view thereof;

FIG. 3 is a top elevational view thereof;

FIG. 4 is a bottom elevational view thereof;

FIG. 5 is a right side elevational view thereof;

FIG. 6 is a left side elevational view thereof; and,

FIG. 7 is a front right side perspective view thereof.

The broken line showing in FIG. 7 depicts a portion of the design in which the design is embodied that forms no part of the claimed design.
